UNITED STATES PATENT OFFICE.

WILLIAM H. DE BUSK, OF CHICAGO, ILLINOIS, ASSIGNOR TO THE P. & M. COMPANY, OF CHICAGO, ILLINOIS, A CORPORATION OF ILLINOIS.

RAIL ANCHOR.

Application filed March 5, 1923. Serial No. 622,956.

To all whom it may concern:

Be it known that I, WILLIAM H. DE BUSK, a citizen of the United States, residing at Chicago, in the county of Cook, and State 5 of Illinois, have invented certain new and useful Improvements in Rail Anchors, of which the following is a specification.

My invention relates to rail anchors for preventing the longitudinal creeping of railroad rails, and has for its principal object the provision of a new and improved combination of parts, by which an anchor 10 may be tightened in position on a rail.

My invention relates more particularly to 15 the type of anchor in which bearings are provided on the upper faces of the flanges at opposite sides of a rail, with a bearing on the bottom face of the rail at a point located between the points of bearing on the upper 20 faces of the flanges, the arrangement being such that the anchor is tightened into operative engagement when moved laterally with respect to the rail, such tightening being attained by reason of a differential action 25 at opposite sides of the rail. In one form of construction, the tightening is effected by reason of the fact that upon a transverse movement of the anchor upon the rail, the bearing on the upper face of the flange at 30 one side is moved vertically with respect to the bottom face of the rail a greater distance than is the bearing on the upper face of the flange at the opposite side of the rail.

In another form of construction the tightening is effected by reason of a differential 35 leverage. It is one of the objects of my invention to improve devices of both types, both in the matter of obtaining the tightening effect and also in the matter of preventing the anchor from loosening after its 40 application to the rail.

It is another object of my invention to improve devices of this type in sundry details, hereinafter pointed out. The preferred means by which I have accomplished 45 my several objects are illustrated in the drawings and are hereinafter specifically described.

That which I believe to be new and desire 50 to cover by this application is set forth in the claims.

In the drawings:

Fig. 1 is a face view of one form of my improved anchor in operative position on

a rail, the rail being shown in cross-section 55 with the head of the rail broken away, the normal shape of the device from which it is distorted in its application to the rail being indicated by dotted lines.

Fig. 2 is a view similar to Fig. 1, but 60 showing the anchor in a preliminary position in the course of its application to the rail, and showing in dotted lines the position which the device has when the tightening operation is about to begin. 65

Fig. 3 is a top plan view of a cast wedge illustrated in Figs. 1 and 2.

Fig. 4 is a top plan view of a rolled strip ready to be cut into a plurality of wedges.

Fig. 5 is a view similar to Fig. 1, but 70 showing a modified form of wedge, and a modified form of anchor device.

Fig. 6 is another view similar to Fig. 1, illustrating the use of my improved means for holding the anchor device from loosening 75 on the rail.

Fig. 7 shows the form of device illustrated in Figs. 1 and 2, but applied and tightened upon a rail having flanges whose upper faces are parallel with the bottom face of the 80 rail; and

Fig. 8 is a view similar to Fig. 7, but showing a modified form of device.

Referring first to Figs. 1, 2 and 3: 10 and 11 indicate the flanges at the opposite 85 sides of a rail, and 12 indicates the web of the rail, the upper faces of the flanges 10 and 11 being sloped as is usual in connection with American railroad rails. 13 indicates the body of the anchor device, having a bearing 14 against the bottom face of the rail, and being bent inwardly at its ends to provide jaws 15 and 16 adapted to press downwardly upon the upper faces of the flanges 10 and 11, such downward pressure 95 being applied either by direct contact of the jaw with the flange, or by the use of an interposed plate or wedge 17. The anchor is preferably applied to the rail closely adjacent to the cross-tie 18, as is usual with 100 devices of this type. In the construction illustrated in Figs. 1 and 2, the plate 17 interposed between the jaw 16 and the upper face of the flange 11, is in the form of a wedge with its thicker portion disposed adjacent to the outer edge of the flange. As is shown by dotted lines in Fig. 1, the normal shape of the anchor device is such that

the bearing 14 would normally stand at some little distance above the bottom face of the rail, in the applied position of the anchor, the arrangement being such in this regard that it is necessary to distort the anchor by moving the bearing 14 downwardly with respect to the ends of the jaws 15 and 16, against the resilient action of the bar making up the anchor device, in the application of the device to the rail.

The device of Fig. 1 is applied to the rail in the well understood manner. The position in solid lines in Fig. 2 shows the preliminary position with the anchor engaging the rail at the end of the jaw 16. A subsequent position of the device, in the application of the anchor to the rail, is shown by dotted lines in said Fig. 2, in this position the anchor being in engagement with the rail at the bearing 14 and also at each of the jaws. That is to say, in the dotted line position, the anchor is just ready for its tightening upon the rail. Such tightening is effected by raising the jaw 15 into position above the edge of the flange 10, and either driving or otherwise forcing the body 13 and the jaws transversely towards the right in said Fig. 2 with respect to the rail and with respect to the wedge 17, until the anchor assumes the position shown in solid lines in Fig. 1, with the end of the jaw 16 in engagement with a shoulder 19 formed on the upper face of the wedge. As will be readily understood, the jaw 16 will snap into engagement with the shoulder 19 as soon as the anchor has been moved sufficiently to the right in Fig. 1, to permit such engagement. In the applied position of the anchor, the sides of the jaw 16 also contact the ribs or shoulders 20, formed upon the wedge so as to prevent displacement of the wedge longitudinally of the rail from its engagement with the jaw 16.

In the construction illustrated in Figs. 1 and 2, the distance between the bearing 14 of the body of the anchor and the bearing of the jaw 15 upon the upper face of the flange 10 is the same as that between the bearing 14 and the bearing of the jaw 16 upon the wedge 17. By reason of this construction, there is no differential leverage at the opposite sides of the rail, but there is a differential action at the opposite sides of the rail by virtue of which the anchor is tightened into operative engagement, such differential action being brought about by the use of the wedge 17 at one side of the rail while the jaw at the opposite side of the rail engages directly with the upper face of the flange.

In the application of the device of Figs. 1 and 2 to a rail, the first tightening of the anchor is effected by raising jaw 15 for operative engagement with the edge of the

flange from the position shown in dotted lines in Fig. 2. The subsequent tightening of the anchor in its application to the rail is due to the fact that as the anchor is moved toward the right in Fig. 2 both the jaws 15 and 16 are moved upwardly with respect to the bottom face of the rail, while the bearing 14 is of course held against upward movement. The resulting distortion of the anchor in its application to operative position causes a very firm grip upon the rail. It will be understood that for the operation of raising the jaw 16 into operative engagement with the flange and for the subsequent movement of the anchor toward the right in Fig. 2, it will be necessary that the wedge 17 be held against lateral movement on the flange towards the right. This holding of the wedge 17 is to be effected in any suitable manner, the wedge being made of such size longitudinally of the rail that a convenient engagement can be effected with the wedge at opposite faces of the jaw 16. The shoulder 19 is to be of such a size as to serve normally for preventing disengagement of the end of the jaw 16 therefrom after such jaw has snapped into contact therewith. It will be understood that when the anchor is to be removed from the rail, the jaw 16 can be readily disengaged from the shoulder 19 by the application of upward pressure on the jaw.

In Fig. 4, I have illustrated the formation of a plurality of wedges 17 integrally by a rolling process, the wedges to be cut from the strip along the dotted lines 21.

In the construction in Fig. 5, the distance between the bearing 14 of the body of the anchor and the bearing of the jaw 15 upon the upper face of the flange 10 is considerably less than the distance between the said bearing 14 and the bearing of the jaw 16 upon the upper face of the interposed plate or wedge 22. Thus there is a differential action at opposite sides of the rail by reason of a differential leverage, as well as by reason of the provision of the wedge 22 which has its thicker portion adjacent to the edge of the flange. In the construction shown in Fig. 5, the wedge 22 is designed to be out of contact with the web 12 of the rail, being provided with a downward extension 23 at one face adapted to engage the edge of the flange 11.

The anchor device of Fig. 6 is similar to that shown in Fig. 5, by which a differential leverage is provided at opposite sides of the rail, but a different form of device is provided for preventing the loosening movement of the anchor upon the rail after its application. The form of device here shown comprises a plate 24 provided with a shoulder 25 pressed in the upper face of the plate, the arrangement being such that

the effective thickness of the plate 24 is the same at the outer edge of the flange as that at the inner edge of the plate adjacent to the web 12. The plate 24 is thus not relied upon for tightening the anchor, but only for holding the anchor against moving in the direction for loosening the anchor upon the rail.

In Fig. 7, I have shown an anchor of the general type illustrated in Figs. 1 and 2, in which there is no differential leverage obtained. In the construction here shown, the flanges 10 and 11 are of even thickness from their outer edges to the vertical web 12; that is to say, the upper faces of the flanges 10 and 11 are parallel with the bottom face of the rail. The tightening of the anchor upon the rail is attained by reason of the differential action brought about by the use of the wedge 26, which is very similar to the wedge 17 of the construction illustrated in Figs. 1 and 2. In the construction shown in Fig. 7, however, the wedge 26 is provided with a shoulder 27 adapted to engage the end of the jaw 16, but no ribs or shoulders are provided corresponding with the ribs or shoulders 20 of the wedge 17 of Fig. 1.

In the construction shown in Fig. 8, the arrangement is substantially the same as that shown in Fig. 7, except that there is a differential leverage provided in the device of Fig. 8. That is to say, in the anchor of Fig. 8, the distance between the bearing 14 of the body upon the lower face of the rail to the bearing of the jaw 16 upon the wedge device 28 is considerably smaller than the distance between the said bearing 14 and the bearing of the jaw 15 upon the upper face of the flange 10. It is thus seen that the device of Fig. 8 differs from the device of Fig. 5 in that the shorter lever of the construction of Fig. 8 is that adjacent to the jaw having the clearance required for applying the anchor, rather than at the opposite end of the device, as illustrated in Figs. 5 and 6. Inasmuch as the device of Fig. 8 relies for its tightening upon the differential effect produced by the use of the wedge 28 and not to any extent upon any differential action otherwise, there is an advantage in having the shorter lever in engagement with the wedge 28, rather than with the longer lever in engagement, as is shown in Fig. 5, in which the differential action is attained both by reason of the use of the wedge 22 and also by reason of the fact that the upper faces of the flanges 10 and 11 are sloping downwardly with respect to the bottom face of the rail. By this construction, the desired tightening can be attained by the use of a thinner wedge than could be done otherwise.

In a number of the figures, the jaw 15 is shown as being beveled at its inner end,

so as to provide for the possibility of driving the anchor into applied position after such beveled portion has been brought into engagement with the upper edge of the outer face of the flange 10. The end of the jaw 16 is also shown as being beveled in a number of the figures in order to avoid undesirable contact with the web 12 in the initial position of the anchor upon the rail. If desired, the wedge device can be inserted between the jaw 16 and the upper face of the flange 11 after the jaw 16 has been hooked over the flange, as shown in solid lines in Fig. 2.

By my construction, as exemplified in the several forms shown, I have provided an anchor which has a very strong grip upon a rail; means is provided for holding the anchor from a loosening movement on the rail without the necessity for pressing a shoulder in the metal of the bar, it being understood that such shoulder can be produced much more readily in the wedge 17 which is cast or rolled, than it can in the bar which is made of comparatively higher grade metal; by the provision of a variety of sizes and shapes of wedges 17, a single size and shape of the bar member of the anchor can be used effectively with any one of a very considerable number of different rails differing from each other very largely as to size, as to the angle of slant of the upper faces of the flanges, and as to other factors. Indeed, by the use of a wedge such as is illustrated, the anchor can be tightened effectively upon rails or beams upon which this general type of anchor or holding device could not be tightened at all without the use of such a wedge or some similar expedient.

So far as I am aware, I am the first in the art to provide a wedge, or plate, or other device, adapted by engagement with the end of one of the jaws by means of a shoulder or otherwise, to prevent the body and the jaws from movement in the direction for loosening upon the rail, such plate, wedge, or other device having operative engagement with some portion of the rail for preventing movement of such part inwardly toward the web 12.

So far as I am aware, I am the first in the art to provide for the use of a wedge between one of the jaws of an anchor of the type here described and the upper face of the adjacent flange, such wedge being disposed with the thicker portion thereof adjacent to the outer edge of the flange.

While I prefer to employ one of the constructions as illustrated in the several figures of the drawings, it will be understood that I do not wish to be restricted to the use of such constructions, except so far as the details of such constructions are covered by the claims, since it is evident that many

changes may be made in the details of the constructions without departing from the spirit of my invention.

I claim:

- of the rail, the body comprising a bearing for the bottom face of the rail located between the jaws, the parts being so arranged that the device is applicable to a rail from 5 one side thereof, and a wedge interposed between the jaw and the upper face of the flange at that side of the rail toward which the body is moved transversely for the tightening operation serving to cause said jaw to 10 move upwardly with respect to the upper face of the adjacent flange as said jaw moves towards the outer edge of the flange.
9. A rail anchor comprising a body adapted to extend across the bottom face of a rail, 15 jaws carried by said body and overlying the upper faces of the flanges at opposite sides of the rail, the body comprising a bearing for the bottom face of the rail located between the jaws, the parts being so arranged 20 that the device is applicable to a rail from one side thereof, and means interposed between one of the jaws and the upper face of the adjacent flange serving to cause the jaw to move upwardly with respect to the upper 25 face of the adjacent flange as the jaw moves towards the outer edge of the flange and comprising means adapted by engagement with the end of said jaw normally to prevent movement of the jaw in the direction 30 for loosening on the rail.
10. A rail anchor comprising a body adapted to extend across the bottom face of a rail, jaws carried by said body and overlying the upper faces of the flanges at opposite 35 sides of the rail, the body comprising a bearing for the bottom face of the rail located between the jaws, the parts being so arranged that the device is applicable to a rail from one side thereof, and a wedge interposed 40 between one of the jaws and the upper face of the adjacent flange with the thicker portion of the wedge disposed adjacent to the outer edge of the flange, the arrangement being such that when the body and jaws are 45 moved laterally with respect to the wedge and with respect to the rail into operative position on the rail, a differential movement of the jaws is obtained with respect to the flanges serving to tighten the anchor on the 50 rail, said wedge being provided with a shoulder on its upper face adapted by engagement with the adjacent jaw normally to prevent movement of the body and jaws in the direction for loosening on the rail.
- 55 11. A rail anchor comprising a body adapted to extend across the bottom face of a rail, jaws carried by said body and overlying the upper faces of the flanges at opposite sides of the rail, the body comprising a bearing for the bottom face of the rail located midway between the portions of said jaws which bear on the flanges of the rail, the parts being so arranged that the device is applicable to a rail from one side thereof, and means interposed between one of the jaws and the upper face of the adjacent flange adapted to cause the jaw to move upwardly with respect to the upper face of the flange as said jaw moves towards the outer edge of the flange serving to tighten the anchor upon the rail.
12. A rail anchor comprising a body adapted to extend across the bottom face of a rail, jaws carried by said body and overlying the upper faces of the flanges at opposite sides of the rail, the body comprising a bearing for the bottom face of the rail located midway between the portions of said jaws which bear on the flanges of the rail, the parts being so arranged that the device is applicable to a rail from one side thereof, and a wedge interposed between one of the jaws and the upper face of the adjacent flange with the thicker portion of the wedge disposed adjacent to the outer edge of the flange, the arrangement being such that when the body and jaws are moved laterally with respect to the wedge and with respect to the rail into operative position on the rail, a differential movement of the jaws is produced with respect to the rail, serving to tighten the anchor on the rail.
13. A rail anchor comprising a body adapted to extend across the bottom face of a rail, jaws carried by said body and overlying the upper faces of the flanges at opposite sides of the rail, the body comprising a bearing for the bottom face of the rail located midway between the portions of said jaws which bear on the flanges of the rail, the parts being so arranged that the device is applicable to a rail from one side thereof, and means interposed between one of the jaws and the upper face of the adjacent flange adapted to cause the jaw to move upwardly with respect of the upper face of the flange as said jaw moves towards the outer edge of the flange serving to tighten the anchor upon the rail, and comprising means adapted by engagement with the end of said jaw normally to prevent movement of the body and jaws in the direction for loosening on the rail.

WILLIAM H. DE BUSK.
